UNITED STATES PATENT OFFICE

118,871

DESIGN FOR A MEDAL OR THE LIKE

Harold C. Vaisey, Rochester, N. Y., assignor to Hickok Manufacturing Company, Inc., Rochester, N. Y., a corporation of New York

Application August 15, 1939, Serial No. 86,706

Term of patent 3½ years

To all whom it may concern:

Be it known that I, Harold C. Vaisey, a citizen of the United States, residing at Rochester, in the county of Monroe and State of New York, have invented a new, original, and ornamental Design for Medals or the like, of which the following is a specification, reference being had to the accompanying drawing, forming part thereof.

In the drawing:

Fig. 1 is a front elevational view of a medal showing my new design.

Fig. 2 is an edge view of the same.

The present design appears on the front face only of the medal, the rear face thereof being devoid of features of ornamentation.

I claim:

The ornamental design for a medal or the like, substantially as shown and described.

HAROLD C. VAISEY.
